UNITED STATES PATENT OFFICE.

NICHOLAS LALLI, OF PHILADELPHIA, PENNSYLVANIA.

DESIGN FOR A RADIOSPEAKER.

Application filed February 11, 1926. Serial No. 16,488. Term of patent 14 years.

To all whom it may concern:

Be it known that I, NICHOLAS LALLI, a subject of the King of Italy, having declared my intention of becoming a citizen of the United States, residing in Philadelphia, Pennsylvania, have invented a new, original, and ornamental Design for Radiospeaker, of which the following is a specification, reference being had to the accom-

panying drawing, forming part thereof, in which—

Figure 1 is a front elevation of the radio speaker, and

Fig. 2 is a side elevation.

I claim:

The ornamental design for a radiospeaker, as shown.

NICHOLAS LALLI.
